CLAIM

The ornamental design for a mat for developing hand-to-eye coordination in infants, as shown and described.

DESCRIPTION

FIG. 1 is a top perspective view of a mat for developing hand-to-eye coordination in infants showing my new design;

FIG. 2 is an end elevational view thereof, the opposite end being a mirror image of that shown, except for the air valve;

FIG. 3 is a side elevational view thereof, the opposite side being a mirror image of that shown;

FIG. 4 is a top plan view thereof; and,

FIG. 5 is a bottom plan view thereof.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 336,660
DATED : June 22, 1993
INVENTOR(S) : Linda F. Dial

It is certified that error appears in the above-identified patent and that said Letters Patent is hereby corrected as shown below:

On the title page, in item [54] and in column 1, line 2,
in the title change "MAX" to --MAT--.

Signed and Sealed this

Eleventh Day of January, 1994
